COMBING AND MASSAGE DEVICE

Betty Ruth Nesbitt, Los Angeles, Calif.

Application June 9, 1941, Serial No. 397,165

9 Claims. (Cl. 132—9)

The present invention relates broadly to combing and massaging devices, and in its specific phases to a comb mounted on a thimble.

Large hand combs and so-called rat-tail combs are commonly used for combing and arranging human hair. These combs, however, are difficult to use in making small curls and sculptured curls in beauty work, and also are relatively unsatisfactory for use by furriers in sewing fur. These difficulties led to the making of the present invention which largely overcomes the difficulties noted.

Accordingly, among the objects of the present invention, is the production of a thimble comb adapted to be slipped onto the end of one or more of the operator's fingers to facilitate finger-tip control of curls, the making of pin curls and sculptured curls, the combing out of ringlets, the parting of hair, scalp massaging, and the like.

Another object is to provide a thimble having a comb mounted thereon with teeth extending substantially coaxially therefrom.

Another object is to provide a thimble comb having teeth adapted for combing or massaging purposes.

Another object is to provide a thimble comb wherein the thimble has a comb pivotally mounted thereon.

A further object is to provide a pivoted comb type of thimble comb with a latching means for holding the comb in various positions.

A further object is to provide a thimble comb having a multiplicity of thimbles with a comb extending therefrom and preferably coaxially therewith.

Still further objects and advantages will appear as the description proceeds.

To the accomplishment of the foregoing and related ends, the invention, then, consists of the means hereinafter fully described and particularly pointed out in the claims, the annexed drawing and the following description setting forth in detail certain means for carrying out the invention, such disclosed means illustrating, however, but several of various ways in which the principle of the invention may be used.

In said annexed drawing:

Figure 1 shows an elevational view of a thimble comb with the comb mounted in fixed position on the end of the thimble.

Figure 2 shows a center sectional view of a thimble comb taken along the line 2—2 of Figure 1, looking in the direction of the arrows.

Figure 3 is a side view of a thimble comb look-

ing at the edge of the comb portion, the teeth of which are inclined sidewise as shown.

Figure 4 shows an elevational view of a thimble comb with the comb mounted for pivoting to various positions on the thimble.

Figure 5 shows a side view of the thimble comb assembly illustrated in Figure 4.

Figure 6 is an enlarged fragmentary sectional view of a preferred form of the pivoted comb latching mechanism as taken along line 6—6 of Figure 4, looking in the direction of the arrows.

Figure 7 shows an elevational view of a thimble comb having multiple thimbles.

Referring more particularly to Figures 1 and 2 of the drawing, one form of the thimble comb consists of a thimble 1 which has a small comb 2 mounted on the end of same and coaxial therewith. The teeth of the comb have been shown as

relatively thick and stubby for convenience of illustration and it is to be understood that such showing is merely diagrammatic of the various types of rigid, flexible, tubular, bristle, or other forms of teeth suited to the carrying out of the principles of the present invention. The thimble is made hollow and provided with an open end 3 for the insertion of the user's finger. For convenience the thimble may be made in various sizes adapted to fit varying size fingers, and to facilitate holding same on the operator's finger, the thimble may be slightly flattened, tapered in slightly from the inlet end, or both, and for simplicity of illustration, the various figures are to be considered as diagrammatically showing constructions of this nature as well as plain cylindrical forms. This comb and thimble assembly may also be made of various materials, for instance, metal, rubber, "Celluloid," "Bakelite," or any other suitable plastic material of various resin or cellulose base types. The assembly further is not limited to the use of one material since obviously the comb and thimble may be made of different materials, suitably joined together, without departing from the scope of the present invention.

Instead of having a straight tooth flat comb extending substantially coaxially from the end of the thimble, as shown in Figures 1 and 2, this comb may be made of various shapes, and one typical construction of a variation of this nature is shown in Figure 3, where the comb illustrated has a substantially hook-shaped end profile. This particular construction is especially adapted for massage combing when the comb 2a is made of soft rubber or the like, and the thim-

ble 1a is also of soft rubber, or, if desired, of hard material, such as metal, plastics, or the like, to which comb 2a has been joined in any one of various ways.

A variation of the construction shown in Figures 1, 2, and 3 is illustrated in Figure 7, wherein comb 2b is mounted on a pair of thimbles 1b and 1c, and preferably coaxially therewith. The construction as thus shown is intended, for simplicity of illustration, to diagrammatically show a thimble comb construction having a plurality of thimbles adapted for operation in unison, and wherein the teeth of the comb are either straight across, tapered, inclined, or the like.

While comb 2 may be mounted in fixed position on thimble 1 as is typically illustrated in Figures 1, 2, and 3, a more versatile assembly may be made by pivotally mounting the comb on the thimble as is shown diagrammatically in Figures 4 and 5. In this construction, the thimble 1d is preferably provided with bosses 4 and 5, and comb 2c with a cut-away portion 6 terminating in end members 7 and 8. Pivot pins 9 and 10 may be used to pivotally join end members 7 and 8 to bosses 4 and 5. The holding of comb 2c in various positions may be accomplished in several ways, and one of the most convenient of these is to provide thimble 1d with a series of rib-like bosses 11 adapted to be engaged by latch members 12 and 13 (Figure 6) mounted on comb 2c by rivet 14, or the equivalent. Latch members 12 and 13 are preferably provided with outwardly sloping ends 15 and 16 to facilitate disengagement of the latch at the will of the user, and to aid in automatically elevating the corresponding latch member for reengaging the next rib-like boss 11 which same is forced over. The pivoted comb construction is not limited to use on a single thimble, but rather same may be incorporated in a multiple thimble comb, and for simplicity of illustration, it is intended that Figure 7 be considered as diagrammatically showing this general type of construction.

In use the beauty operator, furrier, or other user, slips the thimble or thimbles of the thimble comb or combs on one or more fingers and then utilizes the comb portion thereof for the particular purpose then required, for instance scalp massaging, parting the hair, making pin curls, sculptured curls, making or combing out ringlet curls, or the like. Such use of the finger comb makes possible faster work, easier formation of various types of curls, and in general makes possible the ready accomplishment of different forms of work with hair or fur which is difficult with present-day combs.

Other modes of applying the principle of my invention may be employed instead of those explained, change being made as regards the articles and combinations herein disclosed, provided the means stated by any of the following claims or the equivalent of such stated means be employed.

I therefore particularly point out and distinctly claim as my invention:

1. In a device of the character described, the combination which comprises a thimble, and a toothed member mounted thereon, said toothed member having a plurality of teeth in a row and being adapted to extend from the end of said thimble in a plane at least substantially including the axis of said thimble.

2. In a device of the character described, the combination which comprises a thimble, and a member having a substantially flat sided row of teeth mounted thereon and adapted to extend from the end of said thimble substantially in line with a plane including the axis thereof.

3. In a device of the character described, the combination which comprises a thimble with substantially smooth sides, a toothed member having a substantially flat sided row of teeth, the teeth of said toothed member extending outwardly from the end of said thimble, and anchoring means for holding said toothed member in place at the end of said thimble and with the teeth thereof substantially in a plane including the axis of said thimble.

4. A device of the character described, which consists of a thimble, and a comb mounted thereon, said comb being adapted to extend from the end of said thimble and substantially in line with the axis thereof.

5. In a device of the character described, the combination of a plurality of thimbles, said thimbles being joined together in operable position, and a comb mounted on said thimbles.

6. In a device of the character described, the combination of a thimble, a toothed member, pivot means on said thimble, and means for pivotally mounting said toothed member on the pivot means of said thimble.

7. In a device of the character described, the combination of a thimble, a toothed member, fixed pivots on said thimble, means for pivotally mounting said toothed member for rotation about said fixed pivots and over the end of said thimble, and means for anchoring said toothed member at various positions of rotation on said thimble.

8. In a device of the character described, the combination of a thimble, a toothed member, means for pivotally mounting said toothed member for rotation over the end of said thimble, and means for anchoring said toothed member at various positions on said thimble, said anchoring means comprising latch means on said toothed member, and latch engaging means on said thimble.

9. In a device of the character described, the combination which consists of a thimble, and a toothed member having a substantially flat sided row of substantially parallel teeth, said toothed member being permanently anchored to said thimble, and extending from the end thereof in a plane substantially including its axis, said teeth also being substantially parallel to said axis.

BETTY RUTH NESBITT.
